UNITED STATES PATENT OFFICE.

WILLIAM M. REYNOLDS, OF CINCINNATI, OHIO, ASSIGNOR TO THE AMERICAN STEEL ROOFING COMPANY, OF SAME PLACE.

DESIGN FOR A VENTILATOR OR CHIMNEY-CAP.

SPECIFICATION forming part of Design No. 32,750, dated May 29, 1900.

Application filed April 30, 1900. Serial No. 15,017. Term of patent 14 years.

To all whom it may concern:

Be it known that I, WILLIAM M. REYNOLDS, a citizen of the United States, residing in Cincinnati, Hamilton county, Ohio, (post-office address No. 228 East Front street, Cincinnati, Ohio,) have invented and produced a new and useful Design for a Ventilator or Chimney-Cap, of which the following is a specification, reference being had to the accompanying drawing, forming part thereof, the drawing being a side elevation of a ventilator or chimney-cap showing my new design.

As shown in the drawing, the leading or material feature of my design consists of a

base-collar A, a superposed conical crown B, ¹⁵ and a band C, surrounding the base of the crown, the cross-sectional contour of the band being a convex curve, the upper and lower portions of the band curving inwardly.

Having described my invention, what I ²⁰ claim as new, and desire to secure by Letters Patents, is—

The design for a ventilator or chimney-cap, as herein shown and described.

WILLIAM M. REYNOLDS.
